Application December 16, 1949, Serial No. 6,672

Term of patent 14 years

(Cl. D54—2)

To all whom it may concern:

Be it known that we, Ralph W. Haman, Alfred B. Girardy and Donald W. Doman, citizens of the United States of America, and residents, respectively, of Flossmoor, county of Cook and State of Illinois, Chicago, county of Cook and State of Illinois, and Harvey, county of Cook and State of Illinois, have invented a new, original, and ornamental Design for a Spandrel Panel, of which the following is a specification, reference being had to the accompanying drawings, forming part thereof.

In the drawings—

Fig. 1 is a general front elevational view of the spandrel panel of our new design;

Fig. 2 is a perspective view of the panel showing its surface contour; and

Fig. 3 is a fragmentary perspective view showing the actual surface contour of the panel to larger scale.

What is claimed is:

The ornamental design for a spandrel panel, substantially as shown.

RALPH W. HAMAN.
ALFRED B. GIRARDY.
DONALD W. DOMAN.
